SWITCH CONTROL SYSTEM

Bernard E. O'Hagan, Swissvale, Pa., assignor to
 The Union Switch & Signal Company, Swiss-
 vale, Pa., a corporation of Pennsylvania

Application September 22, 1938, Serial No. 231,229

6 Claims. (Cl. 246—242)

My invention relates to a control system for the motor for operating a railway track switch.

It has heretofore been proposed to provide an overload relay having a winding energized in accordance with the current taken by the motor, and having a contact which becomes picked up when the motor current exceeds a predetermined value for longer than a predetermined time. The overload relay contact when picked up effects interruption of the motor circuit to prevent injury to the motor.

It has also been proposed heretofore to provide a holding winding either as a part of the overload relay or as a part of a separate relay, this winding being energized on picking up of the overload relay contacts and being operative when energized to establish a circuit to maintain itself energized. This winding controls means which operates when the winding is energized to maintain the energizing circuit for the switch motor interrupted.

It has been proposed to provide means operable when the dual selector lever is in the hand-throw position to energize the holding winding and thus prevent operation of the switch motor while the dual selector lever is in the hand-throw position or until such time thereafter that the position of the switch control lever is changed.

The arrangement heretofore employed is such, however, that the holding winding will operate to effect interruption of the switch motor circuit only as long as the winding is energized, and if for any reason the supply of current to the winding is interrupted the holding winding will fail to prevent operation of the switch motor.

It is an object of my invention to provide a control system including a relay having a winding which is normally energized, and which is deenergized on picking up of the overload relay contacts in order to effect interruption of the switch motor circuit.

A further object of my invention is to provide an improved control system of the type described and incorporating means operable on movement of the dual selector lever to the hand-throw position to effect deenergization of the said winding and thus interrupt the switch motor circuit.

Another object of my invention is to provide a control system of the type described and arranged so that on deenergization of the winding mentioned above it will not again become energized until the dual selector lever is returned to its normal position and the position of the switch control lever is thereafter changed.

A further object of my invention is to provide an improved switch motor control system.

Other objects of my invention and features of novelty will be apparent from the following description taken in connection with the accompanying drawing.

In the drawing the single figure is a diagrammatic view showing one system embodying my invention.

Referring to the drawing, the reference character W designates a railway track switch which is operated by the well-known dual selector type of mechanism. In the form here shown diagrammatically this mechanism includes a dual selector lever S which operates a link 3. When the dual selector lever S is in the normal position, as shown in the drawing, link 3 connects switch W with the motor M, while when the lever S is in the reverse position, link 3 no longer connects the switch W to motor M but instead connects the switch to a hand-throw lever H.

The switch W operates a motor cut-out contact 5 in accordance with the position of the switch. The contact 5 is arranged so that it engages a contact 6 in all positions of the switch W except the normal position thereof, and so that it engages a contact 7 in all positions of the switch W except the reverse position thereof.

The dual selector lever S operates contacts 9 and 10 in such a manner that when the dual selector lever is in the normal position, that is the position in which it is shown and in which it conditions the switch W for operation by the motor M, contact 9 engages contacts 12 and 13, while contact 10 engages contacts 14 and 15. In the hand-throw position of the dual selector lever S the contacts 9 and 10 do not engage the stationary contacts associated therewith.

The control system includes a suitable control device provided with a movable member or element having a normal position in which it establishes circuits for the switch motor to cause the motor to move the switch to the normal position, this member or element also having a reverse position in which it establishes circuits for the switch motor to cause the motor to move the switch to the reverse position.

As shown in the drawing, this control device comprises a polarized switch control relay WR having a winding which is energized by current supplied over control wires 20 and 21. The relay WR has an armature which operates contacts 23, 24 and 25, while the armature is movable between a normal and a reverse position in ac-

cordance with the direction of energization of the relay winding.

5 A control lever L, which is mounted at a point remote from the switch W, such as in an interlocking tower, operates contacts 27 and 28 to control the polarity of the current supplied from a battery 30 to control wires 20 and 21. When the control lever L is in the normal position, as shown, contact 27 connects control wire 20 to terminal B of a battery 30 and contact 28 connects control wire 31 to terminal C of the battery 30 to thereby effect the supply of current of normal relative polarity to the control wires 20 and 21.

10 15 When the control lever L is in the reverse position, contact 27 connects control wire 20 to terminal C of battery 30, while contact 28 connects control wire 21 to terminal B of battery 30 to thereby effect the supply of current of reverse relative polarity to the control wires 20 and 21.

20 25 The polar contact 23 of relay WR is connected by a wire 32 to one brush of the motor armature 33 of the switch motor M, while polar contact 24 is connected by a wire 35 to the other brush of the motor armature.

30 35 Polar contact 23, when in its normal position as shown, engages a normal polar contact 37 which is connected by wire 38 to stationary contact 15, while a branch of wire 38 is connected to reverse polar contact 39 which is adapted to be engaged by a polar contact 24. Stationary contact 15 is engaged by movable contact 10 in the normal position of the selector lever S, while the contact 10 also engages stationary contact 14 which is connected by wire 40 to terminal B of battery 42.

40 45 Polar contact 23 of relay WR, when in its reverse position, engages reverse polar contact 44 which is connected by wire 45 to stationary contact 7 which at times is engaged by the switch operated contact 5. In similar manner, polar contact 24 of relay WR, when in its normal position as shown, engages normal polar contact 47 which is connected by wire 48 to stationary contact 6 which is engaged at times by switch operated contact 5.

50 55 Switch operated contact 5 is connected by wire 49 to one terminal of the field winding 50 of the motor M, while the other terminal of the winding 50 is connected by a wire 51 to one terminal of a resistance unit 53 and to one terminal of the winding of the overload relay OR. The other terminal of the resistance unit 53 and of the winding of the overload relay OR are connected by a wire 55 to a contact 56 of relay ORP. A branch of wire 55 is connected to movable contact 58 of relay OR, while the contact 58 when released engages stationary contact 59 which is connected by a wire 60 to one terminal of the winding of relay ORP.

60 65 The resistance unit 53 has a positive thermal coefficient of resistance, that is the resistance of the unit increases as the temperature of the material of which the unit is constructed increases. The resistance unit 53 and the overload relay OR are arranged and proportioned so that under normal operating conditions most of the current flowing in the circuit of the switch motor flows through the resistance unit 53 and 70 too little current flows in the winding of the relay OR to cause the contact 58 to be picked up. Accordingly, contact 58 remains released.

75 On flow of an unusually heavy current in the circuit of the switch motor for an abnormally long time interval, such as occurs when move-

ment of the switch is obstructed, the material of which the resistance unit 53 is constructed becomes heated, thereby increasing its resistance and causing an increase in the flow of current in the winding of relay OR sufficient to effect picking up of the relay contacts.

80 The relay ORP has a movable contact 62 to which is connected wire 64 leading from terminal C of battery 42, while the contact 62 when picked up engages stationary contact 56.

85 The contact 25 of relay WR controls a circuit for energizing the winding of the relay ORP. Contact 25 is operated by the armature of the polar relay WR and is of the make-before-break type. When the relay armature is in the normal 15 position, as shown, contact 25 engages normal polar contact 66 to which is connected a branch of wire 64 leading from terminal C of battery 42, and when the relay armature is in the reverse position, the contact 25 engages a reverse polar contact 68 to which is connected a branch of wire 55.

90 95 The movable contact 25 and the stationary contacts 66 and 68 are arranged and constructed so that on movement of the armature of the relay WR from its normal position to its reverse position, the contact 25 will engage contact 68 before it is moved out of engagement with contact 66. Similarly, on movement of the relay armature from its reverse to its normal position, the contact 25 will engage contact 66 before it is moved out of engagement with contact 68. It will be seen, therefore, that on movement of the relay armature from one of its positions to the other, there is a brief time interval in which the movable contact 25 is in engagement with the contacts 66 and 68 to thereby establish a circuit from wire 64 leading from terminal C of battery 42 to wire 55 leading to one terminal of the winding of relay ORP.

100 105 The equipment is shown in the drawing with the switch W, the control lever L, and the dual selector lever S in their normal positions, with the overload relay OR released, and with the relay ORP energized. As the control lever L is in the normal position, current of normal relative polarity is supplied to the control wires 20 and 21 and the polar contacts of the relay WR are in their normal positions, while the circuit for energizing the switch motor M is interrupted by the switch operated contact 5.

110 115 At this time the contact 58 of relay OR is released and the winding of relay ORP is energized by current supplied over a circuit which is traced from terminal B of battery 42 through wire 40, 55 dual selector lever contact 9, wire 61, winding of relay ORP, wire 60, contacts 59—58 of relay OR, wire 55, contacts 56—62 of relay ORP and wire 64 to terminal C of battery 42.

120 125 If at this time the operator wishes to effect movement of the switch W from its normal to its reverse position, he may do so by moving the control lever L from its normal to its reverse position. On this movement of the control lever L, the contacts 27 and 28 are operated to effect the supply of current of reverse relative polarity from battery 30 to control wires 20 and 21, and on the supply of energy of this relative polarity, the polar contacts of relay WR are moved from their normal positions to their reverse positions to thereby establish a circuit to energize the switch motor M to cause it to move the switch to the reverse position.

130 135 The energizing circuit for the switch motor M is traced from terminal B of battery 42 through 75

wire 40, dual selector lever contact 10, wire 38, reverse polar contacts 39—24 of relay WR, wire 35, motor armature 33, wire 32, reverse polar contacts 23—44 of relay WR, wire 45, contact 7, switch operated contact 5, wire 49, motor field winding 50 wire 51, resistance unit 53 and winding of relay OR in multiple, wire 55, contacts 56—62 of relay ORP, and wire 64 to terminal C of battery 42.

10 As a result of this supply of current to the motor M, the switch W is caused to move to the reverse position and when it reaches the reverse position, contact 5 is moved out of engagement with contact 7, thereby interrupting the circuit 15 for energizing the switch motor.

In like manner, if when the switch W is in the reverse position the operator desires to move it to the normal position, he may do so by returning the control lever L from its reverse to its 20 normal position. On this movement of the lever L, the contacts 27 and 28 are operated to supply current of normal relative polarity to the control wires 20 and 21, and the polar contacts of relay WR are caused to move to their normal 25 positions as shown, thereby establishing circuits to energize the switch motor M to cause it to move the switch W from the reverse to the normal position.

The energizing circuit for the switch motor M 30 is traced from terminal B of battery 42 through wire 40, selector lever contact 10, wire 38, normal polar contacts 37—23 of relay WR, wire 32, motor armature 33, wire 35, normal polar contacts 24—47 of relay WR, wire 48, contact 6, switch 35 operated contact 5, wire 49, field winding 50 of switch motor M, wire 51, resistance unit 53 and winding of relay OR in multiple, wire 55, contacts 56—62 of relay ORP, and wire 64 to terminal C of battery 42.

40 As a result of this energization of the switch motor M, the switch W is moved from the reverse to the normal position and when the switch reaches the normal position, contact 5 is moved out of engagement with contact 6 to thereby interrupt the energizing circuit for the switch motor.

This control system is arranged so that if while the switch W is being moved from one of its positions towards the other of its positions 50 further movement of the switch is prevented because of an obstruction, the contact of the overload relay OR will become picked up, thereby de-energizing the winding of the relay ORP with the result that contact 62 of relay ORP interrupts 55 the circuit for the switch motor to thereby prevent injury to the switch motor.

For purposes of illustration, it will be assumed that the switch W is being moved from the normal to the reverse position and that further movement of the switch is prevented before the switch reaches the reverse position.

On the occurrence of the obstruction to movement of the switch, there is an increase in the flow of current in the circuit of the switch motor 60 and therefore in the resistance unit 53. When this increased flow of current has continued for a predetermined length of time, the temperature of the resistance unit 53 is increased to such an extent that the resistance of the unit increases and causes a sufficient increase in the flow of current in the winding of the relay OR sufficient to effect picking up of the contact 58 of the relay OR.

On picking up of the contact 58 of the relay 75 OR, the circuit for energizing the winding of

relay ORP is interrupted, and contact 62 of relay ORP becomes released to interrupt the energizing circuit for the switch motor M. On interruption of the circuit of the switch motor, current is no longer supplied to the winding of the relay OR and contact 58 of this relay becomes released to again engage contact 59. However, on release of contact 58, the circuit for the winding of relay ORP is not reestablished since contact 62 of relay ORP is released, thereby interrupting the circuit 10 from terminal C of battery 42 to contact 58.

If following the interruption of the switch motor circuit due to an obstruction of the switch the operator wishes to return the switch to the position from which it was being moved when 15 the obstruction occurred, he may do so by returning the control lever L to its former position, in this case the normal position. As a result of this movement of the control lever L, current of normal relative polarity is supplied to 20 the control wires 20 and 21 and the polar contacts of the relay WR are moved to their normal positions to establish circuits to energize the switch motor M to cause it to move the switch 25 to the normal position. The energizing circuits for the switch motor M, however, do not become complete until the winding of the relay ORP is energized. This winding is energized on this movement of the contacts of the relay WR in a 30 manner about to be described.

As previously explained, the contact 25 of relay WR is arranged so that on movement of the armature of the relay from one of its positions to the other, contact 25 will be in engagement with both contact 66 and contact 68 for a time interval. When contact 25 engages both of the contacts 66 and 68, a circuit is established to energize the winding of relay ORP, this circuit being traced from terminal B of battery 42 through wire 40, selector lever contact 9, wire 61, winding 40 of relay ORP, wire 60, contacts 59—58 of relay OR, wire 55 to reverse polar contact 68 of relay WR, contact 25, normal polar contact 66, and wire 64 to terminal C of battery 42.

The equipment is arranged so that on movement of the armature of the relay WR between its two positions, the contact 25 establishes a circuit between contacts 66 and 68, and thereby energizes the winding of relay ORP, for a long enough period of time to effect picking up of 50 contact 62 of the relay. On picking up of contact 62, a stick circuit is provided for the winding of relay ORP to maintain the winding energized after contact 25 ceases to establish connection between contacts 66 and 68. The stick circuit 55 includes wire 64, contacts 62—56 of relay ORP, wire 55, contacts 58—59 of relay OR, and wire 60 leading to a terminal of the winding of relay ORP.

On picking up of contact 62, the energizing circuit for the switch motor M is complete, and the polar contacts of the relay WR being in their normal positions the switch motor M is energized in a manner to cause it to move the switch W to the normal position.

In similar manner, if while the switch is in 65 the reverse position and is being moved to the normal position movement of the switch is obstructed, contact 58 of the overload relay OR will interrupt the circuit for the winding of the relay ORP, and relay ORP will thereupon interrupt 70 the switch motor circuit and thus prevent injury to the switch motor. The switch W may then be returned to the reverse position by moving the switch control lever L to the reverse position, while on this reversal of the polarity of 75

the current supplied to the control wire, the armature of the relay WR will be moved to its reverse position and contact 25 will momentarily establish a circuit to energize the winding of relay ORP, and thus reestablish the switch motor circuit in the manner just described in detail.

The control system provided by this invention is arranged in such a manner that on movement of the dual selector lever S to the hand-throw position, the winding of the relay ORP is deenergized, thereby interrupting the circuit of the switch motor, and so that on return of the dual selector lever to the normal position, the winding of the relay ORP will not again become energized until there is a change in the position of the control lever L subsequent to return of the dual selector lever S to the normal position.

On movement of the dual selector lever S to the hand-throw position, contacts 9 and 10 are moved out of engagement with the stationary contacts associated therewith. On movement of contact 9 out of engagement with contacts 12 and 13, the circuit from terminal B of battery 42 through wire 61 leading to a terminal of the winding of relay ORP is interrupted and contact 62 of relay ORP becomes released, thereby interrupting the switch motor circuit at one point. In addition, on movement of contact 10 out of engagement with contacts 14 and 15, the connection from wire 40 leading from terminal B of battery 42 to wire 38 is interrupted, thereby interrupting the energizing circuit of the switch motor M at another point. It will be seen, therefore, that as long as the dual selector lever S is in the hand-throw position, the switch motor circuit is interrupted and the switch motor M cannot be energized to cause movement of the switch W.

On return of the selector lever S to the normal position, contact 10 is moved into engagement with contacts 14 and 15, thereby reestablishing the circuit from wire 40 to wire 38. However, the energizing circuit for the switch motor continues to be interrupted at this time since contact 62 of relay ORP is released.

On return of selector lever S to the normal position, contact 9 again establishes connection between contacts 12 and 13 to thereby establish a circuit from terminal B of battery 42 to wire 61 leading to one terminal of the winding of relay ORP. However, at this time no connection is established from wire 60, leading from the other terminal of the winding of relay ORP, to terminal C of battery 42 and hence the winding of relay ORP does not become energized. A circuit is not established from wire 60 to terminal C of battery 42 since contact 62 of relay ORP is released and since contact 25 of relay WR does not bridge contacts 66 and 68.

It will be seen, therefore, that on return of the selector lever S to the normal position, a circuit is not reestablished to energize the winding of relay ORP and contact 62 continues to interrupt the circuit for energizing the switch motor M.

The winding of the relay ORP will become energized, however, as soon as there is a change in the position of the control lever L, and therefore in the position of the polar contacts of relay WR.

On a change in the position of the control lever L and consequent reversal in the polarity of the current supplied to the control wires 20 and 21, the polar contacts of relay WR are shifted from one position to the other, and during this

movement of the polar contacts, contact 25 momentarily bridges contacts 66 and 68, thereby establishing a circuit from wire 64, leading from terminal C of battery 42, to wire 55 which is connected by contacts 58-59 of relay OR to wire 60 leading to a terminal of winding ORP. The winding of relay ORP, therefore, is energized and contact 62 becomes picked up to establish a stick circuit for the relay winding and to complete the circuit for energizing the switch motor. If at this time the switch W and the control lever L are out of correspondence, the switch motor M will move the switch W to the position corresponding to that occupied by the control lever L. Similarly, if at the time the contact 62 of relay ORP becomes picked up, the switch W and the lever L are in correspondence, the energizing circuit for the switch motor will be interrupted by switch operated contact 5 and the motor, therefore, will not be energized and will not move the switch.

From the foregoing it will be seen that on movement of the selector lever S from the normal position to the hand-throw position, the relay ORP is operated to remove the switch motor M from control of the control lever L, and that on return of the selector lever S to the normal position, the relay ORP is not conditioned to restore control of the switch motor to the control lever L until there is a change in the position of the control lever L. This mode of operation is desirable as it insures that if, while the selector lever is in the hand-throw position, the position of the control lever L is changed, then on return of the selector lever S to the normal position the switch motor M will not be energized to effect movement of the switch W to the position corresponding to that occupied by the control lever L. There is, therefore, no storage of switch control while the selector lever S is in the hand-throw position.

In addition, it will be seen that the relay ORP is conditioned to establish the switch motor circuit only when the relay winding is energized and that on deenergization of the relay winding, it interrupts the circuit for the switch motor. Accordingly, if for any reason the winding of the relay ORP is not energized at a time when it should be energized, the relay contact will open and will interrupt the switch motor circuit to prevent undesired operation of the switch motor as long as the winding of relay ORP remains deenergized.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a switch control system, in combination, a railway track switch movable between a normal and a reverse position, a motor for moving said switch, a control device having a movable member having a normal position and a reverse position, the movable member being operable in the normal position to establish a normal supply circuit through which current may be supplied to the motor to cause it to move the switch to the normal position, said movable member being operable in the reverse position to establish a reverse supply circuit through which current may be supplied to the motor to cause it to move the switch to the reverse position.

- the switch to the reverse position, means for effecting movement of the control device movable member between its two positions, an auxiliary relay having contacts included in said motor supply circuits, said contacts being closed when and only when the winding of the said relay is energized, a holding circuit for energizing said auxiliary relay winding, said holding circuit including contacts of said relay closed when and only when the relay winding is energized, the control device movable member having associated therewith mechanism actuated by movement of the said member from one of its positions to the other to also establish a circuit for energizing the winding of the auxiliary relay, said mechanism being ineffective to establish such circuit for the winding of the auxiliary relay when the control device movable member is in either its normal or its reverse position, and means responsive to the magnitude of the current taken by the switch motor for interrupting the auxiliary relay holding circuit.
2. In a switch control system, in combination, a railway track switch movable between a normal and a reverse position, a motor for moving said switch, a control device having a movable member having a normal position and a reverse position, the movable member being operable in the normal position to establish a normal supply circuit through which current may be supplied to the motor to cause it to move the switch to the normal position, said movable member being operable in the reverse position to establish a reverse supply circuit through which current may be supplied to the motor to cause it to move the switch to the reverse position, means for effecting movement of the control device movable member between its two positions, an auxiliary relay having contacts included in said motor supply circuits, said contacts being closed when and only when the winding of the said relay is energized, a holding circuit for energizing said auxiliary relay winding, said holding circuit including contacts of said relay closed when and only when the relay winding is energized, the control device movable member having associated therewith mechanism operable during movement of the said member from one of its positions to the other to also establish a circuit for energizing the winding of the auxiliary relay, said mechanism being ineffective to establish such circuit for the winding of the auxiliary relay when the control device movable member is in either its normal or its reverse position, means responsive to the magnitude of the current taken by the switch motor for interrupting the auxiliary relay holding circuit.
3. In a switch control system, in combination, a railway track switch movable between a normal and a reverse position, a motor for moving said switch, a pair of conductors, means for supplying current of one relative polarity or the other to said conductors, a polarized relay energized from said conductors, said relay having polar contacts having a normal position in which a normal supply circuit is established through which current may be supplied to the motor to cause it to move the switch to the normal position, said polar contacts also having a reverse position in which a reverse supply circuit is established through which current may be supplied to the motor to cause it to move the switch to the reverse position, an auxiliary relay having contacts included in said motor supply circuits, said contacts being closed when and only when the relay winding is energized, the polarized relay having make-before-break contacts closed only during movement of its polar contacts between their normal and reverse positions to establish a pick-up circuit for energizing the winding of the auxiliary relay, a holding circuit for energizing the auxiliary relay winding, said holding circuit including contacts of said auxiliary relay closed when and only when the winding of said relay is energized, and means responsive to the magnitude of the current taken by said motor for interrupting the auxiliary relay holding circuit.
4. In a switch control system, in combination, a railway track switch movable between a normal and a reverse position, a motor for moving said switch, a pair of conductors, means for supplying current of one relative polarity or the other to said conductors, a polarized relay energized from said conductors, said relay having polar contacts having a normal position in which a normal supply circuit is established through which current may be supplied to the motor to cause it to move the switch to the normal position, said polar contacts also having a reverse position in which a reverse supply circuit is established through which current may be supplied to the motor to cause it to move the switch to the reverse position, an auxiliary relay having contacts included in said motor supply circuits, said contacts being closed when and only when the relay winding is energized, the polarized relay having make-before-break contacts closed only during movement of its polar contacts between their normal and reverse positions to establish a pick-up circuit for energizing the winding of the auxiliary relay, a holding circuit for energizing the auxiliary relay winding, said holding circuit including contacts of said auxiliary relay closed when and only when the winding of said relay is energized, and means responsive to the magnitude of the current taken by said motor for interrupting the auxiliary relay holding circuit.
5. In a switch control system, in combination, a railway track switch movable between a normal and a reverse position, a motor for moving said switch, a pair of conductors, means for supplying current of one relative polarity or the other to said conductors, a polarized relay energized from said conductors, said relay having polar contacts having a normal position in which a normal supply circuit is established through which current may be supplied to the motor to cause it to move the switch to the normal position, said relay polar contacts having a reverse position in which a reverse supply circuit is established through which current may be supplied to the motor to cause it to move the switch to the reverse position, an auxiliary relay having

contacts included in said motor supply circuits, said contacts being closed when and only when the relay winding is energized, the polarized relay having contacts closed when and only when 5 its polar contacts are being moved between their normal and reverse positions to establish a pick-up circuit for energizing the winding of the auxiliary relay, a holding circuit for energizing the auxiliary relay winding, said holding circuit 10 including contacts of said relay closed when and only when the winding of said relay is energized, a dual selector element movable between a normal position in which it conditions the switch for operation by the motor and a hand-throw 15 position in which it conditions the switch for manual operation, and means controlled by said element and operative in the hand-throw position thereof to interrupt the auxiliary relay holding circuit, said means being operative in the 20 normal position of said element to establish a circuit through which current may be supplied to the auxiliary relay winding.

6. In a switch control system, in combination, a railway track switch movable between a normal 25 and a reverse position, a motor for moving said switch, a pair of conductors, means for supplying current of one relative polarity or the other to said conductors, a polarized relay energized from said conductors, said relay having polar 30 contacts having a normal position in which a normal supply circuit is established through which current may be supplied to the motor to

cause it to move the switch to the normal position, said polar contacts having a reverse position in which a reverse supply circuit is established through which current may be supplied to the motor to cause it to move the switch to the reverse position, an auxiliary relay having contacts included in said motor supply circuits, said contacts being closed when and only when the relay winding is energized, the polarized relay having contacts closed when and only when its polar 10 contacts are being moved between their normal and reverse positions to establish a pick-up circuit for energizing the winding of the auxiliary relay, a holding circuit for energizing the auxiliary relay said holding circuit including contacts 15 of said auxiliary relay closed when and only when the winding of said relay is energized, means responsive to the magnitude of the current taken by said motor for interrupting the auxiliary relay holding circuit, a dual selector 20 element movable between a normal position in which it conditions the switch for operation by the motor and a hand-throw position in which it conditions the switch for manual operation, and means controlled by said element and operative 25 in the hand-throw position thereof to interrupt the auxiliary holding circuit relay, said means being operative in the normal position of said element to establish a circuit through which current may be supplied to the auxiliary relay 30 winding.

BERNARD E. O'HAGAN.
